UNITED STATES PATENT OFFICE.

JOHN W. LAMBERT, OF ANDERSON, INDIANA.

MIXING DEVICE FOR GASOLENE-ENGINES.

SPECIFICATION forming part of Letters Patent No. 634,242, dated October 3, 1899.

Application filed July 2, 1898. Serial No. 685,047. (No model.)

To all whom it may concern:

Be it known that I, JOHN W. LAMBERT, a citizen of the United States, residing at Anderson, in the county of Madison and State of Indiana, have invented certain new and useful Improvements in Mixers for Gasolene-Engines, of which the following is a specification, reference being had therein to the accompanying drawings, in which—

10 Figure 1 is a vertical sectional view of my device; Fig. 2, a detail end view of the spraying-cone, and Fig. 3 a horizontal section on the line 3 3 of Fig. 1. Figs. 4 and 5 are views showing the manner of connecting the mixer to the engine.

15 Referring to the drawings by letters, *a* designates the intake-pipe of the engine-cylinder *b*, this pipe being provided with a depending branch *b'* at or near its closed end *c*.
20 Surrounding the depending branch *b'* of the intake-pipe is a gasolene cup or reservoir *d*, which is closed at its ends and is preferably formed integral with the said intake branch. Projecting into the intake-pipe is a chamber *e*, which is formed integral with the wall of 25 said intake-pipe and communicates with the gasolene-cup, so as to fill with gasolene when the cup is filled to the proper level. A pipe *f* is connected to the gasolene-cup and to a suitable tank *g*, containing gasolene, a small pump *h* being employed to replenish the gasolene as it is used, this pump being automatic in its operation by reason of a suitable connection to the engine, the connection shown 30 consisting of a pivoted lever *h'*, adapted to be depressed by a cam *h²*, carried by a suitable shaft *h³*, said lever *h'* bearing upon and actuating the spring-retracted plunger *h⁴* of the pump. The desired level is maintained in 35 the cup by means of a suitable overflow-pipe *i*, connecting the cup to the gasolene-tank.

40 Formed in the chamber *e* is a vertical passage *j*, which connects at its lower end with the gasolene-chamber and at its upper end with the interior of the intake-pipe, this passage being arranged centrally with reference to the intake-pipe. This passage is closed and opened and regulated by means of a suitable cock, which in the present instance consists of a horizontal stem *k*, extending in 45 through the walls of the gasolene-cup and the

intake-pipe and the upper wall of chamber *e*, its inner end being tapered and fitted into a similarly-tapered socket intersecting the vertical passage *j*, this tapered portion being 55 provided with a transverse passage adapted to register with said passage *j*. The stem *k* is provided with an operating hand-wheel *l* at a point outside of the gasolene-cup, and it is held in place by means of a suitable gland *m*, screwed into the casing and bearing against the shoulder *n* on the stem, this gland being provided with an angular head to permit it to be readily adjusted. It will be observed that the stem *k* is entirely inclosed by a horizontal cylindrical casing *o*, formed integral with the walls of the parts through which the stem passes. The stem is limited in its rotative movement by means of a pair of angle-arms *p*, carried by a collar rigidly, but adjustably, attached to a stem between the gland *m* and operating-wheel *l*, the extremities of these arms extending inward and adapted to strike against the opposite side of an intermediate lug *q*, projecting laterally from 65 the gasolene-cup.

70 It will be observed that the suction created through the intake-pipe by the movement of the engine-piston will create a partial vacuum therein and the pressure of the atmosphere 80 will force the gasolene up through central passage *j*, sending it up into the intake-pipe in the form of a jet, the volume of which will be governed by the cock or valve, said passage *j* and its chamber *e* forming a sort of 85 nozzle. Over the exits of passage *j* is a wire-gauze *r*, which will break up the jet partially, and at a suitable point above the wire-gauze is suspended a spraying-cone *s*, this cone being inverted and having its apex directly in 90 line with passage *j*. The inclined surface of the cone is provided with spirally-arranged ribs to receive the impact of the jet and spray the same, giving the finely-communited spray a spiral motion. It is obvious, however, 95 that the arrangement of the ribs may be varied at will, it being simply essential that the cone be provided with suitable projections, preferably inclined with reference to the face of the cone, so that the jet will be 100 broken up in fine particles upon striking the cone. The inverted cone is adjustably sup-

ported by means of a vertical stem *t*, threaded down through the upper side of the intake-pipe and locked in its adjusted position by a lock-nut *u*.

- 5 It will be observed that with this simple device the requisite amount of gasoline will be drawn out of the cup at each pulsation of the engine and will be finely sprayed and vaporized and thoroughly mixed with the in-
10 going air before introduction into the cylinder, this thorough admixture being secured by the peculiar spiral direction the spiral ribs on the cone impart to the ingoing spray, as evident. It will also be observed that the
15 invention is not confined to the specific features of construction shown and described.

Having thus fully described my invention, what I claim, and desire to secure by Letters Patent, is—

- 20 1. In a gasoline-engine, the combination with its intake-pipe, a jet-nozzle supported therein and having its exit end directed inward in the direction of the suction, a gasoline-holder connected to this nozzle, means
25 for maintaining a predetermined level in the gasoline-holder, an inverted spraying-cone supported in the intake-pipe in the path of the jet and with its apex directed toward the jet, this cone being provided on its inclined
30 face with spirally-arranged ribs, whereby the jet will be broken up and the spray given a spiral motion on its way to the engine and be

thoroughly mixed with the air as and for the purposes set forth.

2. In combination with the intake-pipe of a 35 gas-engine, said intake-pipe being provided with a depending branch pipe, a gasoline cup or tank surrounding this branch, a chamber *e* being formed integral with the branch and projecting into the path of the ingoing air 40 and provided with a jet-nozzle, this chamber *e* being in communication with the gasoline-cup, and said nozzle being formed in the inner wall of the chamber *e* centrally of the intake branch and having a passage *j* extending 45 from the lower part of chamber *e*, below the gasoline-level, up through the upper wall of said chamber *e*, a horizontal stem-valve *k* extending in through the walls of the chamber *e* and branch pipe and gasoline-cup 50 and controlling the jet-passage *j*, a cylindrical casing *o* surrounding this stem throughout its length, means for maintaining the level of the gasoline in the gasoline cup and chamber *e*, and a device in the intake-pipe and 55 above the jet-nozzle for breaking up the jet.

In testimony whereof I hereunto affix my signature, in the presence of two witnesses, this 29th day of June, 1898.

JOHN W. LAMBERT.
